UNITED STATES PATENT OFFICE.

WILLIAM D. HALKET, OF SAN FRANCISCO, CALIFORNIA.

RETORT-DOOR.

1,200,102.

Specification of Letters Patent. Patented Oct. 3, 1916.

Application filed April 20, 1915. Serial No. 22,601.

To all whom it may concern:

Be it known that I, WILLIAM D. HALKET, a citizen of the United States, residing in the city and county of San Francisco and 5 State of California, have invented new and useful Improvements in Retort-Doors, of which the following is a specification.

This invention relates to a retort door.

One of the objects of the present invention is to provide a simple, rigid, easily operated door, particularly designed for hermetically sealing or closing retorts, digesters, bulkhead openings, or containers in general which are subjected to internal pressure 15 caused by steam, air, water or the like.

Another object of the invention is to provide a door which is cheap and practical to construct; and to provide means for applying a great external pressure which may be 20 uniformly distributed over the door, thus producing an absolutely steam, air or watertight closure.

Further objects will hereinafter appear.

The invention consists of the parts and 25 the construction and combination of parts as hereinafter more fully described and claimed, having reference to the accompanying drawings, in which—

Figure 1 is a front view of the retort, 30 showing the application of the door. Fig. 2 is a cross section on line 2—2, Fig. 1. Fig. 3 is a detail view of the door hinge.

More particularly described, A indicates the retort proper on which is suitably secured a door frame 2. Formed on one side of the frame is a plurality of hinging lugs, such as indicated at 3, and formed in the face of the door frame is an annular dovetail-shaped groove 4 in which a packing material, constructed of rubber, asbestos or like material, is mounted. Adapted to form a hermetic seal or closure for the opening 5 formed in the door frame is a door 6. This door is constructed of cast iron or like suitable material, and it is suitably reinforced with internal ribs 7. The ribs may be placed horizontally or vertically, or both, and a sufficient number may be applied to give the door sufficient strength and rigidity against 45 the pressure applied.

Formed on one side of the door is a pair of lugs 8 which project between the hinge lugs 3. These lugs are provided with elliptical-shaped slots, such as indicated at 9, and 55 a pin 24 extending through the lugs 3 and the elliptical openings in the lugs 8 form

hinges about which the door may be swung. Extending across the face of the door and secured to same, by stud bolts 10', is a pair of cross bars 11. These cross bars are provided for the purpose of forcing the door against the gasket to form a pressure-tight seal between the frame and door. This is accomplished as follows: Referring to Fig. 1, it will be seen that each hinge consists of 60 three sets of lugs 3, 3^a and 3^b and that the door proper is hinged between the lugs 3 and 3^a. Pivotaly mounted between the lugs 3^a and 3^b is a pair of bolts 12, one for each cross bar, which extend through drilled 65 holes 13 formed in the outer ends of the cross bars. The outer ends of these bolts are threaded and are provided with nuts 14 by which the cross bars, with connected door, may be forced inwardly against the packing; 70 the elliptical openings in the door lugs 8 permitting this adjustment.

Formed in the opposite end of each cross bar is a lug 15, and adapted to be swung into and out of engagement with same is a 80 U-shaped link 16 which is pivotally mounted, as at 17, on lugs 18 formed on the door frame. Mounted in the outer end of each link 16 is a screw lever 19, which, when in register with lug 15, may be turned to force 85 the bars and connected door inwardly against the packing.

A great external pressure may thus be applied to the door by means of the nut 14 and the screw lever 19, and this pressure may be 90 evenly distributed on the face of the door by means of clamps 20 fitted between the webs of the bars. One pair of clamps 20 has been provided for each cross bar and the position of each clamp may be independently 95 adjusted by means of an adjusting screw, such as indicated at 21. An external pressure may thus be evenly distributed over the face of the door and a perfect seal produced against the internal pressure caused 100 by steam, air or water.

Formed on the face of the door, under each cross bar, is a pad or reinforcing face plate 22 which may be planed to form a perfect seat for the clamping members 20 105 and bars. The inner contacting face of each cross bar is also preferably slightly convexly curved to permit the central portion of same to engage the center portion of the door. Three contacting points may thus be 110 made by each cross bar as the bar will engage the center of the door while the clamp-

ing members 20 will engage the outer edges more or less, thus evenly distributing the pressure applied.

Referring to Fig. 1, it will be seen that 5 the upper hinge bolt 24 is sufficiently extended to pass through a pair of lugs 25 formed on the upper edge of the door frame. Pivotally mounted between said lugs and adapted to swing about the hinge bolt in 10 unison with the door and cross bars is a straining rod or brace 26. The outer end of this rod passes through a lug 27 formed on the door, and a nut 30 mounted on the outer end of this rod not only serves to keep 15 the straining rod in place but may also be tightened up to such an extent as to hold the door in position, or, in other words, to prevent sagging or settling of the door.

A door constructed as here shown is rigid 20 in construction and may be cheaply manufactured and quickly opened or closed in actual practice. It may, furthermore, be adjusted from time to time as the packing compresses or settles both from the hinge 25 side of the door and the lock side. A perfect seal against internal pressure may thus at all times be maintained.

The materials and finish of the several 30 parts of the device are such as the experience and judgment of the manufacturer may dictate.

I wish it understood that various changes in form, proportions and minor details of 35 construction may be resorted to within the scope of the appended claims, and that I do not wish to limit myself to the specific design and construction here shown.

Having thus described my invention, what I claim and desire to secure by Letters 40 Patent is—

1. In a retort door, the combination with a frame having an opening formed therein, of a door adapted to form a closure for said opening, hinge lugs formed on the frame, 45 lugs on the door extending between the hinge lugs, said door lugs having elliptical-shaped openings formed therein, pins extending through the lugs forming pivots about which the door may be swung, cross 50 bars extending across the exterior face of the door and carried by the door, a bolt extending through the outer end of each cross bar, said bolts being carried by the door hinge pins and adapted to swing around same in unison with the door, a nut on the outer end of each bolt, and a pivotally 55 mounted adjustable locking member engageable with the other end of each cross bar.

60 2. In a retort door, the combination with a frame having an opening formed therein, of a door adapted to form a closure for said opening, hinge lugs formed on the frame, lugs on the door extending between the 65 hinge lugs, said door lugs having elliptical-

shaped openings formed therein, pins extending through the lugs forming pivots about which the door may be swung, cross bars extending across the exterior face of the door and carried by the door, said cross bars presenting slightly curved faces so as to contact with the door midway between their ends, a bolt extending through the outer end of each cross bar, said bolts being carried by the door hinge pins and adapted to swing 70 around same in unison with the door, a nut on the outer end of each bolt, a pivotally mounted adjustable locking member engageable with the other end of each cross bar, and a pair of independently adjustable 75 clamping members engageable with the face of the door mounted in each cross bar.

3. A closure of the character described comprising a frame having an opening formed therein, a door hinged on the 80 frame to form a closure for the opening, a pair of cross bars extending across the face of the door, adjustable hinge connections between one end of each cross bar and the frame, means for forcing the other ends of 85 the cross bars against the frame, a strain rod connected at one end with the upper hinge and having its other end extending through a lug on the door, and a nut on said end engageable with the lug. 90

4. In a retort door, the combination with a frame having an opening formed therein, of a door adapted to form a closure for said opening, hinge lugs formed on the frame, lugs on the door extending between the 100 hinge lugs, said door lugs having elliptical-shaped openings formed therein, pins extending through the lugs forming pivots about which the door may be swung, cross bars extending across the exterior face of the door and carried by the door, said cross bars presenting slightly curved faces so as to contact with the door midway between their ends, a bolt extending through the outer end of each cross bar, said bolts being 110 carried by the door hinge pins and adapted to swing around same in unison with the door, a nut on the outer end of each bolt, a pivotally mounted adjustable locking member engageable with the other end of each 115 cross bar, a pair of independently adjustable clamping members engageable with the face of the door mounted in each cross bar, a strain rod connected at one end with the upper hinge and having its other end extending through a lug on the door, and a nut on said end engageable with the lug. 120

5. The combination with a frame having an opening formed therein and a door adapted to form a closure for the opening, 125 of hinge lugs formed on the frame, lugs on the door having elongated openings formed therein, pins extending through the lugs forming pivots about which the door swings, means engageable with the door on 130

the end opposite to the hinges to force this end of the door against the frame, and means engageable with the hinge end of the door to force this end of the door against 5 the frame.

6. The combination with a door and a pair of hinge lugs, of a bolt pivotally mounted between the hinge lugs, a cross-bar on the door through which the pivotally 10 mounted bolt extends and a nut on the bolt engageable with the cross-bar to adjust the position of the door with relation to the hinge lugs.

7. The combination with a door, of a cross-bar being curved on its inner side as 15 described, a bolt adjustably securing each end of the cross-bar to the door, a pair of adjusting screws mounted in the cross-bar and engageable with the surface of the door,

a door frame having an opening formed 20 therein which the door is adapted to close, a pair of hinge lugs on the door frame, a bolt having one end pivotally mounted in said lugs and the other end extending through one end of the cross-bar, a nut on 25 the bolt engageable with the arm to adjust the position of the door with relation to the hinge lugs, and means engageable with the opposite end of the cross-bar to force the door against the frame.

In testimony whereof I have hereunto set my hand in the presence of two subscribing witnesses.

WILLIAM D. HALKET.
